UNITED STATES PATENT OFFICE.

STEPHEN P. WALLING, OF SOUTH EDMESTON, NEW YORK.

GRINDING-MILL.

SPECIFICATION forming part of Letters Patent No. 252,158, dated January 10, 1882.

Application filed July 26, 1881. (No model.)

To all whom it may concern:

Be it known that I, STEPHEN P. WALLING, of South Edmeston, in the county of Otsego and State of New York, have invented certain 5 Improvements in Grinding-Mills, of which the following is a specification.

My invention relates to grinding-mills, and more particularly to the step and bearings by which the lower and upper ends of the spindle 10 are supported.

The invention also consists in other details hereinafter explained.

In the accompanying drawings, Figure 1 represents a side elevation of my improved mill; 15 Fig. 2, a vertical central section of the same; Fig. 3, a perspective view of the step and its supporting parts separated one from another; Fig. 4, a horizontal section through the upper bearing of the spindle, on the line $\alpha\alpha$ of Fig. 20 1; Fig. 5, a view of the band or cord employed to close the space between the curb and its top or cover.

The primary object of my invention is to provide means whereby the bearings of the spindle may be accurately adjusted to properly support the spindle, avoid excessive friction or undue play, and compensate for wear. To this end I provide a stationary box or chamber at the center of the base or bed of the mill-frame, 25 preferably casting the same in one piece therewith, as hereinafter explained, within which box or chamber are suspended a step and bearings, the former from a yoke supported or carried by the bridge-tree, and the latter by a 30 flange at its upper end, resting upon a shoulder or ledge in the box or chamber. The step is furnished with a self-adjusting bearing-plate, and the side bearings of the spindle are formed by blocks passing radially through openings in 35 an encircling cage or cylinder suspended or sustained by a flange within the box or chamber, as mentioned. The side bearing-blocks are pressed inward by set-screws passing through the walls of the box or chamber within which 40 the step and cage are suspended. An oil-passage is formed in the lower end of the spindle, passing upward through the center and opening outward at the side, in order to facilitate the delivery of oil to the end of the spindle and 45 its bearing-plate. The upper end of the spin-

dle is supported in essentially the same manner as the lower end; but the bearing-blocks, instead of being mounted in a separate cage, are seated in recesses formed in the supporting-frame. The top or cover of the chamber containing the grinding-disks is supported upon elastic cushions, the space between the curb and top being closed by an encircling band or cord. 55

Referring now to the drawings, A represents the frame and casing of the mill, the curb *a*, its bottom or floor *b*, the supporting-columns *c*, and the bed or base *d* being preferably formed in a single casting. The base or bed *d* is provided with a fixed central box or chamber, B, preferably cast therewith, adapted to receive 65 the step and bearings of the spindle C, as shown in Fig. 2.

The construction of the step and bearing will be clearly understood by referring to Figs. 2 and 3, in which D represents the step, provided in its upper face with a cavity to receive a bearing-plate, *f*. The bottom of the cavity or the lower face of the bearing-plate is made convex in order that the plate may rock and adjust itself to the end of the spindle; and the 70 plate is provided with ribs or feathers *g*, which project into recesses *h* to prevent the turning of the plate.

The step D is suspended from a yoke, E, by rods *i*, the ends of which are formed with suitable heads and seated in cavities formed in the sides of the central opening of the yoke and in the sides of the step D. A cage or cylinder, F, is interposed between the step D and yoke E, its upper end being provided with a 80 flange to rest upon a shoulder within the box or chamber, and its sides being grooved, as shown at *j*, to receive the suspending-rods *i*.

The sides of the cage or cylinder are provided with radial openings or passages *k* to 85 receive the bearing-blocks G, which are urged against the sides of the spindle by set-screws H, passing through the walls of the box or casing B.

All tendency of the cage F to turn is overcome by a set-screw, K, passing through the wall of the box or case B and bearing directly against the cage, this screw being tightened before the bearing-blocks are adjusted. 95

The yoke E is formed with vertical arms *l*, 100

the lower ends of which are rounded to rest in slight cavities or depressions in the upper face of the bridge-tree I, said bridge-tree being supported at one end upon a pivot, arranged to 5 encircle the box or casing B, and sustained at its outer end by a screw rod or stem provided with an adjusting-nut, J. The yoke being thus supported, it will be seen that it, together with the step, will rise and fall in a true vertical 10 direction when the bridge-tree is moved, thus avoiding all tendency to cramp or bind the spindle. The upper end of the spindle is carried by a yoke or frame, L, secured upon the top or cover M of the casing of the mill, and 15 formed with a central opening to receive the spindle and with radial cavities to receive the bearing-blocks N, which are pressed against the sides of the spindle by set-screws O.

Vertical play of the spindle is prevented by 20 means of a central screw, P, passing through the top of the yoke or frame L and bearing upon the upper end of the spindle.

The top or cover M is held in position by 25 vertical bolts or rods Q, which are seated at their lower ends in the upper portions of columns e at the sides of the curb or casing, and preferably secured by transverse pins, though it is apparent that they may be secured or held in place by casting the metal around them.

30 The top or cover is formed with ears n, through which the rods pass, the ears resting upon the upper one of a series of washers, o, which in turn rest upon a bed or cushion, p, of rubber or like elastic material, seated in the upper 35 ends of the columns. Nuts q, applied to the rods Q, bear upon the ears to force them down upon the cushions with any desired degree of pressure.

30 The removal of one or more washers permits the top or cover, to the lower face of which one of the grinding-disks is rigidly secured, to be raised or lowered to compensate for wear of the disks, while by the application or removal of washers at the different sides of the curb the 45 adjustment of the top or cover may also be readily effected.

A series of grooves or recesses, r, are formed in the edge of that portion of the top or cover which fits within the curb or casing, to fit over 50 ribs or projections s formed thereon and prevent the turning or shifting of the cover.

The narrow space between the curb and top or cover is closed by a band or cord, R, which is provided with suitable fastenings at its ends, 55 and is passed around the cover or top and united at its ends, as shown. The cord or band prevents the escape of dust, and in a measure relieves the mill of heat and dampness.

As shown in Figs. 1 and 2, the curb or casing is formed with openings S at several points in its sides or walls, closed by wickets or covers T. These openings permit inspection of the interior and greatly facilitate the setting and adjustment of the stones. Any form of 65 cover may be employed, though a simple cap or plate secured to a spring-arm, t, pivoted to the side of the curb or casing, is preferred.

In order to relieve the mill of all jar or shock, I employ, in addition to the elastic cushions beneath the ears of the top or cover, similar cushions beneath the adjusting-nut J and check-plate U, through which latter the screw P passes. For the purpose of oiling the upper bearing of the spindle, the nut P may be provided with a central oil-passage extending through it from end to end, while, in order the better to insure the delivery of oil between the end of the spindle and its bearing-plate, an oil-passage extends from its lower end upward and opens at the side of the spindle into the oil chamber, as 80 shown in Fig. 2.

The runner-stone is supported upon a horizontal bed or plate secured upon the spindle, and is secured by bushing in the ordinary manner. Sufficient space is left between the step 85 and the lower end of the cage to permit all necessary rise and fall of the former, as indicated in the drawings.

I am aware that a continuous ring or packing of elastic hose has been interposed between 90 a millstone and its curb, that wedges and elastic washers have been placed under the ears or lugs of the top or cover of a mill, and that a yoke has been cast with radial cavities open at their upper side. These I do not claim. I am 95 not, however, aware that any one has hitherto provided a band or cord having connecting devices at its ends, whereby it might be applied to and removed from a mill such as described without removing the top of the mill; nor am 100 I aware that washers have been placed below the lugs or ears of a mill-top, as herein explained, so that by increasing or diminishing their numbers the adjustment and elevation of the upper stone might be effected; nor that a 105 yoke has been formed complete in one piece, with radial cavities open only on the inner side, whereby the displacement of the bearing-blocks is prevented so long as the spindle is in place.

Having thus described my invention, what I claim is—

1. In combination with a mill-spindle, a bridge-tree, a yoke supported thereon, a step suspended from said yoke, and a cage supported above the step, encircling the spindle, and provided with adjustable bearing-blocks, substantially as shown and described.

2. In combination with a mill-spindle, a stationary box or chamber provided with radial set-screws, a bridge-tree extending on opposite sides of the same, a yoke supported upon the bridge-tree, a step suspended from the yoke, and a cage encircling the spindle and supported above the step, and provided with radially-moving bearing-blocks adapted to be adjusted by the set-screws, as set forth.

3. The herein-described support for mill-spindles, consisting of a yoke, a step-plate suspended therefrom by headed rods seated in 130 sockets in the yoke and plate, and a rocking bearing-plate seated in the step-plate, substantially as shown.

4. In combination with the step having a

cavity provided with recessed sides, the rocking bearing-plate provided with ribs or feathers to enter said recesses, and thereby prevent the plate from turning.

5 5. In combination with the curb *a*, the rods *Q*, seated in the columns *c*, the elastic cushions *p*, the washers *o*, resting upon said cushions,

the top or cover *M*, provided with ears *n*, resting upon the washers, and nuts *q*, applied to the rods above said ears, substantially as shown. 10
